(57) **CLAIM**

The ornamental design for a rider operated flexible body skate plate, as shown.

DESCRIPTION

FIG. 1 is a Top front perspective view of the invention, showing our new design;

FIG. 2 is a Bottom front perspective view of the invention thereof;

FIG. 3 is a Front elevation view of the invention thereof;

FIG. 4 is a Rear elevation view of the invention thereof;

FIG. 5 is a Top plan view of the invention thereof; and,

FIG. 6 is a Bottom plan view of the invention thereof.
